CARBURETOR

Yesdimir Djordjevitch, Paris, France

Application October 24, 1935, Serial No. 46,620
In France October 24, 1934

6 Claims. (Cl. 261—75)

The apparatuses generally used for atomizing in carburetors are designed and arranged in a manner such that they provide the motor with a mixture made under conditions which are often 5 unfavorable for obtaining the best efficiency of the motor.

My invention has for its object a device which provides the motor with a mixture of air and fuel in proper proportions and which tends to prevent any condensation of the mixture in the 10 principal admission pipe.

To this end the atomizer is given a bell-mouthed shape so as to produce an annular jet of mixture directed towards the crescent shaped 15 spaces left open by the throttle valve without impinging on the axis of said valve. Preferably the body of the atomizer terminates as a cupel having very thin edges and arranged in a divergent, convergent or Venturi-shaped pipe. This cupel is 20 preferably immersed in the fuel and its edges are at a very small distance from the throttled part of this pipe and at the level thereof, whereby the primary air which serves for emulsifying the fuel under the action of the suction exerted by the 25 motor, is laminated between the cupel edges and the throttled part and carries along with it towards the motor the fuel from the edges of the cupel.

I have shown by way of example in accompanying drawings a certain number of forms of execution of my invention.

Fig. 1 shows a carburetor provided with atomizers of the type disclosed by my invention, both in the main spray nozzle and in the idling spray 35 nozzle.

Fig. 2 shows the invention as applied to a reversed or downflow carburetor.

Fig. 3 shows the application of my invention to idling means.

Figures 4 and 5 show the invention applied to a horizontal carburetor.

Figures 6 to 12 show different preferred forms which may be given to my improved atomizer, Figs. 7a, 8a, 9a, 11a, being views from above of 45 the atomizers shown in elevation in Figs. 7, 8, 9, and 11.

The carburetor shown in Fig. 1 comprises a float chamber A, a suction pipe B and the throttle valve C as usual; the atomizer 1 of the spray 50 nozzle fed by the channel D communicating with the float chamber through the calibrated plug V opens towards its outlet end so as to form a cupel 2 with very thin edges and the axis of which coincides with that of the central channel 3 of 55 the atomizer. This cupel is housed in a Venturi-

shaped duct 6, whereby the cupel edges lie in the plane of the narrowest portion 4 of this duct and at a very small distance from the wall of this throttled portion of the venturi. The emulsifying air from the air inlet 1 communicating with the passages 5 surrounding the lower part of the atomizer is laminated and slightly heated between the cupel and the throttled part 4 of the wall. This emulsifying air violently sucked by the motor produces along the edges of the cupel 10 and in the recess thereof an increased depression, and at the same time it atomizes and carries along with it the fuel passing out of the cupel, preferably immersed in the fuel, whereby the air and fuel form a very intimate mixture which is projected along the walls of the duct 6 and the central portion of the throttle valve receives substantially no mixture which would otherwise impinge uselessly on it. The emulsifying air may be either pure or already emulsified, hot or cold, 15 forced under pressure or sucked by the motor.

The idling spray nozzle comprises a similar atomizer 7; but the latter has the edges of its cupel 7' at the level where begins the convergent portion 8 of the duct 6' in which the atomizer 25 opens, the edges of the cupel being here also very near the wall. The driving effect of the air provides again in this case the formation of an annular mixture which is more homogeneous than in the idling spray nozzles used heretofore. 30

As soon as the depression in the motor begins increasing, the flow of emulsifying air surrounding the idling cupel is braked outwardly by the divergent walls surrounding the cupel, whereby the flow of fuel in the cupel is in its turn progressively braked. Obviously it is possible in a carburetor such as that shown, to use only one atomizer of my improved type, the other remaining of the conventional type. 35

The application of my invention to downflow carburetors (Fig. 2) and horizontal carburetors (Figs. 4 and 5) together with the auxiliary means provided therefore is self explanatory from simple inspection of the figures. Another application of the atomizer according to invention is that of Fig. 3 wherein the idling atomizer 7 has its cupel arranged upside down in a duct 6' so as to allow the idling means to cease operation as soon as the motor passes beyond a certain speed or the depression in the duct where the atomizer 40 stands, passes beyond a predetermined value. In effect, this arrangement causes the emulsifying air from the part 13 in the duct, and passing round the cupel of the atomizer, to first carry along with it the fuel in a normal manner; but 50

as soon as the depression begins increasing round the cupel, the emulsifying air impinges with greater strength by reason of its increased flow against the inside of the cupel whereby it brakes 5 more and more the flow of fuel out of the central channel 3' of the atomizer until it stops it entirely.

The atomizer according to my invention may comprise an air admission port opening in its 10 central channel as shown at 9 (Fig. 6). It may also be provided with a vertical notch in a diametrical plane passing through the axis of the throttle valve, whereby the mixture is projected towards the two crescent shaped parts uncovered 15 by the throttle valve when it opens instead of towards the whole periphery of the duct as in the case of Fig. 1. This is the feature illustrated in side and plan views in Figs. 7 and 7a in which the notch is shown at 10. I may also 20 form a larger number of notches and provide all or part of them, if required, with vibratory blades furthering the stirring of the mixture.

Fig. 8 shows an atomizer the cupel of which is closed at 20 and shows only two semi-annual 25 openings 11 which also project the mixture towards the crescent shaped parts uncovered by the throttle valve. These semi-annual openings are connected through the inner chamber 12 with the central channel 3 of the atomizer. This 30 arrangement is of particular advantage when applied to a main spray nozzle such as that of Fig. 1 for which it furthers the regular expansion and separation in two portions of the projected mixture. The same atomizer, as in all the modifications of my invention, may be provided with a complementary air inlet of the type shown on Fig. 6. If required, part of the atomizer may be 35 of a material different, chiefly as concerns conductivity, from the remainder of the atomizer.

Fig. 9 shows a modification of the atomizer according to which the cupel carries at a small distance above it, an auxiliary thin-walled cupel 14 of suitable material provided with a central aperture 14' allowing communication between the 40 space a provided between the two cupels and the upper chamber b closed by a cap 15, whereby the fuel is divided inside the cupel into two streams on either side of a diameter, said streams being shaped as a crescent or half-circle and passing 45 out to either side of the auxiliary cupel. The securing of the cap and auxiliary cupel on to the main cupel is effected preferably along the diameter dividing these streams or else perpendicularly thereto as shown.

Fig. 10 shows a modification according to which the cupel is bound by an oblique plane p, whereby the fuel is directed substantially along lines perpendicular to the throttle valve, and the primary air is submitted to a lamination of varying 50 degree according to the size of the cupel by reason of the different distances between each side of the cupel and the wall of the duct containing the atomizer.

Fig. 11 shows a modification of the atomizer 55 of Fig. 7 in which the diametral notch 10 of predetermined breadth and depth (or the hole or series of holes replacing said notch) is closed at the upper part of the cupel by means of a stationary or vibratory blade 16 which ensures the stirring of the mixture and gives it the desired 60 direction. The blade may be laid flat as shown in Figure 11 or edgewise (Fig. 12). In the latter case the blade is secured to a bridge-piece 18 at the upper end of the notch. I may also provide in place of, or in supplement to the dia-

metrical notch, one or more notches at different points of the cupel and all, or some of which, may, if required, be provided with blades.

I may also stretch across the cupel and substantially along a diameter, a more or less thick 5 wire adapted to further the separation of the mixture into two streams directed to either side of the throttle valve. This has been shown by way of example at 17 in Fig. 6.

Obviously, I may without extending the scope 10 of the invention combine together certain arrangements illustrated in the different figures, and also modify in any suitable manner, the shape, size and material of the parts of the atomizer, as well as the manner of incorporating same 15 in the apparatus requiring it.

What I claim is:

1. In an internal combustion engine, the combination with fuel admission means including a fuel supply, a butterfly type throttle valve and a passageway arranged anteriorly to the throttle valve and showing a frusto-conical portion, of a fuel atomizer arranged in said passageway and comprising a channelled stem and a solid cup-shaped part integral with said stem into which 25 the channel in the stem opens and the wall of which is substantially hemispherical and has a thickness which decreases progressively down to substantially zero between the stem and the outer edge of the cup shaped part, said outer edge 30 lying moreover very near and substantially in the plane of the extremity of the frustoconical portion of the passageway and facing unobstructedly the location of the periphery of the throttle valve when closed.

2. In an internal combustion engine the combination with fuel admission means including a fuel supply, a butterfly type throttle valve and a passageway arranged anteriorly to the throttle valve and showing a frusto-conical portion, of a fuel atomizer arranged in said passageway and comprising a channelled stem and a solid cup-shaped part integral with said stem into which the channel in the stem opens and the wall of which is substantially hemispherical and has a 40 thickness which decreases progressively down to substantially zero between the stem and the outer edge of the cup shaped part, said outer edge 45 lying moreover very near and substantially in the plane of the extremity of the frustoconical portion of the passageway and facing unobstructedly the location of the periphery of the throttle valve when closed, a cover for the cup-shaped part leaving two semi-annual openings between it and the outer edge of said part, said openings 50 facing the location of the periphery of the throttle valve when closed to either side of the pivoting axis of said valve.

3. In an internal combustion engine the combination with fuel admission means including a fuel supply, a butterfly type throttle valve and a passageway arranged anteriorly of the throttle valve and showing a frusto-conical portion, of a fuel atomizer arranged in said passageway and comprising a channelled stem and a solid cup-shaped part integral with said stem into which the channel in the stem opens and the wall of which is substantially hemispherical and has a thickness which decreases progressively down to substantially zero between the stem and the outer 70 edge of the cup shaped part, said outer edge lying moreover very near and substantially in the plane of the extremity of the frustoconical portion of the passageway and facing unobstructedly the location of the periphery of the throttle valve 75

when closed, to the plane of which periphery of the closed valve the plane containing said outer edge is substantially parallel, a cover for the cup-shaped part leaving two semi-annular openings, between it and the outer edge of said part, said openings facing the location of the periphery of the throttle valve when closed to either side of the pivoting axis of said valve.

4. In an internal combustion engine as claimed in claim 1, the provision of notches at two points of the outer edge of the cup-shaped part facing the extremities of the axis round which the throttle valve is adapted to pivot.

5. In an internal combustion engine as claimed in claim 1, the provision of notches at two points of the outer edge of the cup-shaped part facing the extremities of the axis round which the throttle valve is adapted to pivot, and a vibratory member passing through said notches.

6. In an internal combustion engine as claimed in claim 1, the provision of an elongated member stretched across the cup-shaped part in parallelism with the pivoting diameter of the throttle valve.

YESDIMIR DJORDJEVITCH.
